UNITED STATES PATENT OFFICE.

JOHN KIZER LEEDY, OF ROANOKE, VIRGINIA.

RAILROAD-SIGNAL.

SPECIFICATION forming part of Letters Patent No. 752,084, dated February 16, 1904.

Application filed November 10, 1902. Serial No. 130,751. (No model.)

To all whom it may concern:

Be it known that I, JOHN KIZER LEEDY, a citizen of the United States, residing at Roanoke, in the county of Roanoke and State of Virginia, have invented a new and useful Railroad-Signal, of which the following is a specification.

The object of the present invention is to provide an improved signaling system for use in connection with railway-lines; and it consists principally in providing a continuous series of signals placed along the line of the road and visible to all persons on the train, so that the train-crew and passengers will be immediately informed of the presence of another train on the same track as well as the direction in which said train is traveling.

With this and other objects in view the invention consists in the novel construction and arrangement of parts hereinafter described, illustrated in the accompanying drawings, and particularly pointed out in the appended claim, it being understood that various changes in the form, proportions, size, and minor details of the structure may be made without departing from the spirit or sacrificing any of the advantages of the invention.

In the accompanying drawings, Figure 1 is an elevation, partly in the nature of a diagram, illustrating a railway signaling system constructed and arranged in accordance with my invention. Fig. 2 is a side elevation, drawn to an enlarged scale, of a pair of oppositely-facing signaling members forming a part of the system.

At regular intervals along the line of the railroad are placed posts 1, the ordinary telegraph-posts being used for the purpose when available. On each of the posts are secured a number of horizontally-disposed bars 2, placed one above the other and preferably in the form of arrows having distinct heads, one pointing in one direction and the other in the opposite direction. This equipment is used for a single-track railway where trains are moved in both directions, or it may constitute the equipment of a double-track road where trains travel in but one direction on each track. Where three or four or more tracks are employed, a corresponding number of arrows are used, the ar-

rows having suitable designating - marks or being of different color to indicate the track to which they belong. On each of the arrows are arranged a plurality of signaling devices, which may be of the character illustrated in Fig. 2, said signaling devices being arranged near the heads of the arrows, so that they may be readily distinguished. The signaling devices may be of the same or of different color and are of a number corresponding to the number of trains which are allowed on a given section of the road at one time. Generally not more than three trains will be allowed on any one section or block, and I have therefore illustrated three signaling devices on each arrow, although the number may be increased or diminished without departing from the invention. For each signaling device I employ a separate current-conducting wire, and in the present instance six of such wires are employed, as indicated at 5, 6, 7, 8, 9, and 10 in the drawings, the wires extending from station to station and connected to a suitable source of electrical energy, as indicated at 11, and the ends of the wires being grounded to establish circuits. All of the first signals of the upper arrows, as indicated at 12, are connected in series with the line-wire 5. The second set of signals 13 are all connected in series with the line-wire 6, and the third set of signals 14 are connected in series with the line-wire 7. On the lower arrows the signals 15, 16, and 17 are connected, respectively, to the current-conducting wires 8, 9, and 10, so that when any one of the current-conducting wires is connected with the source of electrical energy all of the signals along the line connected to said wire will be energized.

A and B are stations forming the ends of a block, and in each station are arranged arrows corresponding to those on the road and bearing similar signaling devices properly connected to the line-wires, the ends of the wires being connected together and coupled to one pole of the battery and the opposite pole being grounded. In the station A, which may be termed the "sending" station for transmitting signals to the upper set of arrows, each of the line-wires is provided with an independent switch, as indicated at 5', 6', and 7',

- said switches being normally open until a train enters the block or section traveling in the direction indicated by the lower arrows. The station operator then closes the switch 5' and connects the line-wire 5 with the battery, energizing the signals 12 along the whole of the block or section and signaling to both the train-crew and passengers. Should a second train enter the block in the same direction, the train-crew of the second train will be immediately informed of the presence of the preceding train, while the operator will close the switch 6', causing all of the signaling devices 13 to be energized and notifying the persons on the first train that a following train has entered the same section, and in similar manner the entry of a third train on the block or section will be signaled by closing the switch 7'. At the station B the line-wires 5, 6, and 7 are grounded to complete the circuit. Each station constitutes both a sending and receiving station, the station B being provided with normally open switches 8', 9', and 10' for controlling the circuits through the line-wires 8, 9, and 10 and the signals on the lower arrows to which said wires are connected, while at station A these wires are grounded to complete the circuit. Should a train leave station B traveling in the direction of station A, the operator at station B would close the switch 8', energizing all the signals 15 and notifying all trains on the block traveling in the same or in an opposite direction of the entry of the train leaving station B, and in this manner both the train-crew and the passengers are kept informed as to the movements and location of trains, and the safety of the train is not wholly dependent on the firemen and engineer.
- The signals are of any desired construction capable of being operated by an electric current; but preferably I employ incandescent lights, which are connected in series as described, the lights being visible for a long distance. The signals are all protected by hoods or bells 20, as shown more clearly in

Fig. 2. The signals displayed may be of the same or of different color; but preferably the signals 12, 13, and 14 are of a color distinct from the signals 15, 16, and 17, so that there will be no confusion in the reading of signals displayed by the different arrows.

In order to clearly distinguish the wires belonging to different signals, the three wires of each set are preferably provided with wrappings of different color—as, for instance, red, white, and blue—these being assembled by twisting, and the cable thus formed may be provided with a wrapping of a color different from that of similar cables containing wires belonging to a different set of signals.

Having thus described my invention, what I claim is—

A railway signaling system comprising supporting posts, a plurality of superposed arrows secured at an intermediate point to the posts and pointing respectively in opposite directions, a plurality of signaling-lamps secured to the arrows between the points thereof and the point of attachment of the arrows to the posts, the signaling-lamps carried by one arrow being of a color different from the lamps carried by an adjacent arrow, current-conducting wires connecting corresponding signals in series and extending between two separated terminal points or stations, a source of electrical energy disposed at each station and having multiple connection with all of the current-conductors, a plurality of independent switches disposed at one station for closing the circuit through the signals carried by one set of arrows, and corresponding switches disposed at the opposite terminal or station for closing the circuits through the signals carried by the second set of arrows.

In testimony that I claim the foregoing as my own I have hereto affixed my signature in the presence of two witnesses.

JOHN KIZER LEEDY.
